DRILLING APPARATUS

John E. Hoffoss, Houston, Tex., assignor to Reed
Roller Bit Company, Houston, Tex., a corpora-
tion of Texas

Application March 20, 1939, Serial No. 262,888

5 Claims. (Cl. 255—73)

This invention relates to drilling equipment, and more particularly has reference to reaming and coring devices for use in drilling wells in earth formations.

5 The general object of this invention is to provide a device whereby a core may be taken from the formation at the bottom of a well being drilled without the likelihood of forming a crooked hole or encountering other difficulties 10 usually found in taking cores.

The ordinary procedure in coring a well is to run a core drill of a size smaller than the hole which has been drilled up to the taking of the core. This is what is commonly known as "rat-holing ahead." The purpose of drilling such a 15 smaller hole at the bottom of a main hole is to provide a seat at the bottom of the main hole against which a test tool may be set for drill stem testing after the core has been taken.

20 However, in attempting to cut a rat-hole or a hole of smaller diameter in the bottom of the main hole difficulty has been encountered in that when a smaller bit is lowered to the bottom of the main hole and rotated it will tend to start

25 cutting at one side of the main hole rather than at the center thereof. The rat-hole will thus start out eccentric with respect to the main hole and in addition to starting a crooked hole, this will leave an eccentric seat for a testing tool such 30 as above referred to. In the event that casing is set at this point, the cement which is employed about the lower end of the casing will be all on one side of the casing and the possibility of a leak past the cement seal will be greatly increased.

35 Furthermore, if a test tool is run into the hole and an attempt made to test the formation by seating it on the lower end of the main hole with the testing tool projecting into the rat-hole, it will be found almost impossible to obtain a perfect

40 seal with respect to the formation if the formation is firm or hard. On the other hand, if the formation is soft, the testing tool may be forced in but in many instances it will be stuck thereby and it will be found later to be impossible to pull 45 it out of the hole.

It is, therefore, an object of this invention to provide a device which will make it possible to form a rat-hole concentric with the bottom of the main hole in drilling a well.

50 Another object of this invention is to make it possible to take a core with a core drill smaller than the main hole of a well without forming an eccentric or crooked rat-hole.

55 Another object of this invention is to make it

possible to form a more perfect seat for a testing tool at the bottom of the main hole of a well.

Another object of this invention is to make it possible to continue drilling as long as desired with a rat-hole forming bit and provide a structure thereabove which will act both as a guide for such bit and as a reamer for enlarging the rat-hole to the size of the main hole.

Other objects and advantages of this invention will become apparent from the following description taken in connection with the following drawings:

In the drawings:

Fig. 1 is a vertical cross section through the bottom of a well hole showing the effect of ordinary rat-holing and coring methods and apparatus.

Fig. 2 is a similar view showing the start of a rat-holing or coring operation employing the present invention.

Fig. 3 is a similar view showing the well hole and apparatus of Fig. 2 after the drilling has proceeded until the rat-hole is cut to its ultimate depth.

Fig. 4 is a top plan view of the guiding member employed in accordance with this invention.

Fig. 5 is an inside elevation of one section of the guiding and reaming device shown in Fig. 4.

Referring again to Fig. 1, the main hole which has been drilled prior to the coring or rat-holing operation is designated by the numeral 1. After this hole has been completed down to the point 2, the core bit 3 which is of smaller diameter than the main hole 1 is lowered on the drill collar 4 and the usual drill stem. Drilling is then started but due to the fact that there is no positive means for centering the bit 3 on the bottom 2 of the main hole, the bit will tend to dig in at one side of the main hole and form an eccentric rat-hole 5. It will readily be seen that with such a hole, it will not only be impossible to form a perfect seat for a testing tool on the bottom of the main hole about the upper end of the rat-hole, but also when drilling is again resumed with the bit of larger diameter, the presence of the eccentric rat-hole will tend to deflect the path of the larger bit and cause the drilling of a crooked hole.

In Fig. 2 is illustrated the operation of a device constructed in accordance with the present invention. In this figure the core bit 3 is lowered on a drill collar 6 which is similar to the drill collar 4 but differs in that it is provided with a relatively square upwardly facing shoulder 7 adjacent its lower end and with a reduced portion 8 intermediate its lower and upper ends. Adjacent

its upper end the diameter is again increased as shown at 9 but the change in diameter between the portions 8 and 9 is accomplished not by an annular shoulder but by an irregularly formed shoulder having downwardly projecting parts 10 and upwardly projecting grooves 11 therebetween giving the effect of splines on the outer surface of the drill collar. The upper end of the drill collar is connected in the usual manner to the 10 drill stem 12.

Surrounding the portion 8 of reduced diameter is a composite guide member and reaming tool which is illustrated more in detail in Figs. 4 and 5. This member consists of two sections 13 and 14 which are substantially identical and each of which is provided with an ear 15 adjacent one end thereof for a purpose presently to be described. Each of these sections is substantially in the form of a semi-cylinder and is provided intermediate its extremities with a radially projecting blade 16 which operates as a reamer. Each of these sections is also provided with a second radially projecting blade substantially at one extremity thereof as shown at 17 and adapted to be opposed to the ear 15 on the other section. These opposed blades and ears 15 and 17 are provided with apertures for the reception of bolts 18 which cooperate with nuts 19 to secure the two sections together about the reduced portion 8 of the drill collar. Each of the sections 13 and 14 is also provided with a threaded opening adapted to receive a screwed in shear pin 20 and the drill collar is provided with openings 21 for the reception of such shear pins. The sections 13 and 14 are also provided adjacent their upper ends with grooves 22 and splines 23 adapted to engage the grooves and splines 11 and 10 on the drill collar when this element is moved upwardly to its uppermost position on the drill collar. If desired, bearing rings 24 of rubber or other suitable material may be mounted in grooves in the sections to provide a sliding contact with the drill collar.

The operation of the device is as follows: 45 Before lowering the core barrel and drill collar into the well on the usual drill stem, the guiding and reaming member shown in Figs. 4 and 5 is secured about the drill collar in the position shown in Fig. 2. The shear pins 20 are then put 50 in place so as to retain this guiding member in this position on the drill collar during the lowering thereof.* When the device reaches the bottom of the main hole, the reaming and guide member which will be in contact with the side walls of the hole will serve to center the smaller bit 3 so that when rotation begins the smaller bit will begin to dig in substantially concentrically with respect to the main hole, thus forming a concentric rat-hole as shown at 24 in Figs. 2 55 and 3. As this drilling progresses the guiding member will move downwardly with the drill stem until it comes in contact with the shoulder at the bottom of the main hole, whereupon its blades will begin to dig in causing it to drag 60 back and then to move upwardly with respect to the drill collar. This will cause the shearing of

the shear pins 20 and thereafter the guiding and reaming member will remain substantially stationary at the bottom of the main hole until the rat-holing operation has progressed to the point shown in Fig. 3. The drill collar will then have 5 moved downwardly through the guiding and reaming device until the splines 10 and 11 engage the splines 22 and 23, whereupon the guiding and reaming member will again begin to rotate with the drill stem and will be forced downwardly with the drill stem. This will result first in facing the bottom of the main hole so as to provide a perfect seat for any testing tool or the like which may be later lowered into the hole, and will thereafter continue to ream the smaller hole to 15 the size of the larger hole as the drilling progresses. It will thus be seen that a core of any length may be taken without leaving too much of a rat-hole and without in any way impairing the seat which will be formed for a testing tool to be 20 subsequently lowered. At the same time, all of the other objects and advantages sought by this invention will be accomplished.

Having described my invention, I claim:

1. In a drilling apparatus, a drilling tool, and 25 a guiding member carried by said drilling tool above the lower end thereof and slidably upwardly with respect thereto, frangible means for holding said guiding member in its lowermost position while being lowered into a well, said guiding 30 member having reaming blades thereon adapted to enlarge the size of the drilled hole.

2. In a drilling apparatus, a drilling tool, a guiding member carried by said drilling tool above the lower end thereof and slidably upwardly with 35 respect thereto, said guiding member having parts of greater overall diameter than the hole adapted to be formed by said drilling tool, and frangible means for holding said guiding member in its lowermost position while being lowered into a 40 well.

3. In a drilling apparatus, a drilling tool, a reaming tool of larger overall diameter than said drilling tool slidably mounted above said drilling tool for limited sliding movement, means for 45 releasably holding said reaming tool in a lower position with respect to the drilling tool while being lowered into a well, and means for locking said reaming tool against rotation with respect to said drilling tool when in its uppermost position. 50

4. In a drilling apparatus, a drilling tool, a reaming tool of larger overall diameter than said drilling tool slidably mounted above said drilling tool for limited sliding movement, and means for locking said reaming tool against rotation with 55 respect to said drilling tool only when said reaming tool is in its uppermost position.

5. In a drilling apparatus, a drilling tool, a reaming tool of larger overall diameter than said drilling tool slidably and rotatably mounted above 60 said drilling tool for limited sliding movement, and means for locking said reaming tool against rotation with respect to said drilling tool only when said reaming tool is in its uppermost position. 65

JOHN E. HOFFOSS.
